DESIGN FOR A TIRE

James E. Hale, Akron, Ohio, assignor to The Firestone Tire & Rubber Company, Akron, Ohio, a corporation of Ohio

Application February 16, 1940, Serial No. 90,319

Term of patent 14 years

To all whom it may concern:

Be it known that I, James E. Hale, a citizen of the United States, residing at Akron, in the county of Summit and State of Ohio, have invented a new, original, and ornamental Design for a Tire, of which the following is a specification, reference being had to the accompanying drawing forming a part thereof, in which:

Fig. 1 is a perspective view of a tire embodying the new design;

Fig. 2 is a fragmentary perspective view in section thereof;

Fig. 3 is a fragmentary side elevation of the tire; and

Fig. 4 is a fragmentary plan view of the tread portion of the tire.

What is claimed is:

The ornamental design for a tire, substantially as shown.

JAMES E. HALE.
